Primary Examiner — Jennifer L Watkins*Assistant Examiner* — Samantha Lynne Brodowski(74) Attorney, Agent, or Firm — Merchant & Gould P.C.(57) CLAIM

The ornamental design for a bag with handle, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view showing the design;

FIG. 2 is a front view thereof;

FIG. 3 is a first side view thereof;

FIG. 4 is a second side view thereof;

FIG. 5 is a back view thereof;

FIG. 6 is a top view thereof, with the handle shown in an alternate open position; and,

FIG. 7 is a bottom view thereof, with the handle shown in the position of FIG. 1.

The portions shown in broken lines form no part of the claimed design.

1 Claim, 7 Drawing Sheets
